UNITED STATES PATENT OFFICE.

TURNEY G. STOUGH, OF JEANNETTE, PENNSYLVANIA.

DESIGN FOR A TOY CANDY-CONTAINER.

47,122.

Specification for Design.

Patented Mar. 16, 1915.

Application filed January 16, 1915. Serial No. 2,763. Term of patent 14 years.

To all whom it may concern:

Be it known that I, TURNEY G. STOUGH, a citizen of the United States, residing at Jeannette, in the county of Westmoreland and State of Pennsylvania, have invented a new, original, and ornamental Design for Toy Candy-Containers, of which the following is a specification, reference being had to the accompanying drawing, forming a part hereof.

Figures 1 and 2 are elevation views taken from different sides of the device.

I claim:

The ornamental design for a toy candy container, as shown.

TURNEY G. STOUGH.

Witnesses:

FRANK N. GRAY,
H. V. ROWAN.
